UNITED STATES PATENT OFFICE.

CHARLES H. SMITH, OF BOSTON, MASSACHUSETTS.

DESIGN FOR A CLOCK FRONT.

•30,273.

Specification for Design. Patented Jan. 17, 1922.

Application filed March 8, 1921. Serial No. 450,639. Term of patent 7 years.

To all whom it may concern:

Be it known that I, CHARLES H. SMITH, a citizen of the United States, and resident of Boston, county of Suffolk, Commonwealth of Massachusetts, have invented a new, original, and ornamental Design for a Clock Front, of which the following description, in connection with the accompanying drawings, is a specification.

Figure 1 is a front view of the clock front embodying my novel design; and Figure 2, a side view thereof.

I claim:

The ornamental design for a clock front as shown.

In testimony whereof, I have signed my name to this specification.

CHARLES H. SMITH.
